CONTACT FILING DEVICE

Howard Wilson, Brooklyn, N. Y., assignor to
Kastar Incorporated, New York, N. Y., a corporation

Application March 12, 1937, Serial No. 130,599

12 Claims. (Cl. 29—76)

This invention relates to contact filing devices, and more particularly to devices of this character for abrading clean or filing smooth the contact points of circuit making and breaking electrical apparatus, such for example as the distributors of automobiles.

Heretofore when it has become necessary to clean the contact points on the distributor to get rid of the oxides which form on the ends from sparking, it has been customary to retract one of the points, place a small file between the points, and work it back and forth. In doing this the file frequently comes out from between the points, causing much exasperation and delay.

To obviate this difficulty, guide devices have been proposed which are rigidly mounted on the frame or other parts of the electrical device which supports the contacts but these have required extensive framework and a prohibitive amount of manipulation to get ready for the filing operation.

The main objects of the present invention therefore are to provide a simple guide device without extensive framework and which can be readily put into operation without excessive manipulation.

Other objects and features of novelty will be apparent from the following description and the accompanying drawing, in which

80 Figure 1 is a plan view of the device according to the present invention, a small part being broken away to show the construction, the file being in the retracted position;

85 Figure 2 is a side elevation, partly in section along the line 2—2 of Figure 1;

Figure 3 is a view similar to Figure 1 but showing the file in advanced position;

Figure 4 is an inverted plan;

Figure 5 is an end elevation;

90 Figure 6 is a side elevation of a slightly modified form;

Figure 7 is a plan of Figure 6; and

Figure 8 is a section along the line 8—8 of Figure 7.

95 The device according to the present invention comprises an abrading member 10 and a guide member 12. The abrader 10 comprises a stem 13 and a portion provided with an abrasive surface, such as the file blade 14. The guide 12 comprises a sleeve 15 which slidably receives the stem 13, and an end portion 16 which is preferably flat and parallel to the blade 14, and slightly larger than the same. This end portion 16 has an aperture 17 which is adapted to receive the contact point to be filed.

The stem 13 has an enlargement or other stop 18 which engages the outer end of the sleeve 15 to limit the inward movement of the file blade. Outward movement is limited by the shoulder of the end 14 engaging the inner end of the sleeve 15. It should be noted that this stop prevents the file blade from ever being retracted clear of the opening 17, Figures 1 and 4 showing the extreme retracted positions.

In operation, in order to clean contact points such for example as those shown in Figure 2 at 19 and 20, the contact points are separated and the end 16 and the blade 14 are both inserted therebetween, the end 16 being at the same time manipulated until one of the contacts, for example 19, is received in the aperture 17 thereof. The points 19 and 20 are then urged toward each other until both engage the file blade 14. Inasmuch as the end 16 is located by the contact in its aperture 17, the guide cannot escape horizontally or radially, although it may pivot about the contact point.

The blade 14 may now be reciprocated by hand, the portion of the stem 13 beyond the enlargement 18 being grasped as a handle, only one hand being necessary for the filing operation. The stem slides in the sleeve 15 which guides it, the sleeve in turn being located by the contact point in the aperture of the end 16.

The stroke of the abrasive member being limited by the stops described, the abrasive member cannot escape longitudinally, and hence the abrader is maintained in engagement with the contact points until the abrading operation is completed and the points are separated to permit removal of the guide and abrader.

In the modified form shown in Figures 6, 7 and 8, the sleeve 15a is slotted and the file blade 14a is guided in the slot. In this manner the file blade has an upper as well as a lower guide, the bottom of the slot limiting the retractive movement. The slot keeps the blade absolutely parallel to the guide. The flat part 16a of the guide is shorter in this form, but the aperture 17a thereof is spaced from the bottom of the slot a distance which insures that the blade 14a is never retracted clear of the aperture.

It should be noted that the entire device of both forms is very simple in construction and operation. Being little wider than the file, it can be inserted in complicated structures which would offer obstruction to extensive frames, and require removal of parts before such extensive guides could be mounted. Also, the present guide can be inserted and operated by one hand.

the same hand which separates the points for inserting the guide.

What I claim is:

- 5 1. A device for filing contact points which are urged together, comprising in combination, a guide and a member slidable relative thereto and having an abrasive surface, said guide being constructed and arranged to confine said member to rectilinear movement with respect to said guide, said guide having a lateral aperture intermediate its ends and in the path of said member and adapted to engage one of said contact points, when both said guide and member are inserted between said points, whereby said contact point cooperates with said guide to retain said member between said points.
- 10 2. A device for filing contact points which are urged together, comprising in combination, a guide and a member mounted thereon for reciprocation relative thereto, said guide having means for confining said member to rectilinear movement, said member having an abrasive surface, and said guide having a lateral aperture of less width than said abrasive surface in a direction transverse to the path thereof, and adapted to receive one of said contact points when both said guide and member are inserted between said points to hold said guide and member transverse to said points.
- 15 3. A device for filing contact points which are urged together, comprising in combination, a guide and an element slidably mounted relative thereto, said guide comprising a single piece of sheet metal of a width less than half its length, said member having an abrasive surface, said guide having an aperture adapted to receive one of said contact points when both said guide and abrasive surface are inserted between said points, and means for preventing movement of said abrasive surface clear of said aperture.
- 20 4. A device for filing contact points which are urged together, comprising in combination, a guide and a member provided with an abrasive surface, said guide having a portion slidably receiving said member for reciprocation with respect thereto, and means on said guide for engaging the point to be abraded for holding the same transverse to the path of said reciprocation and preventing radial movement of said guide in all directions while permitting pivotal movement thereof with respect to said point to be abraded.
- 25 5. A device for filing contact points which are urged together, comprising in combination, a guide and a member slidable in rectilinear reciprocation thereon having at one end an abrasive surface, said guide having in its end corresponding to said abrasive surface an aperture of less width than said abrasive surface in a direction transverse to the path thereof and adapted to receive and engage one of said contact points when said abrasive surface is inserted between said points.
- 30 6. A device for filing contact points which are urged together, comprising a guide and a file slidable in rectilinear reciprocation relative thereto, said guide having a lateral aperture no wider than the path of said file adapted to re-
- 35 ceive one of said contact points when both said guide and file are inserted between said points, whereby said contact point cooperates with said guide to retain said file between said points.
- 40 7. A device for filing contact points which are urged together, comprising a file blade having a stem, in combination with a guide having a sleeve slidably receiving said stem for rectilinear reciprocation therein and a substantially flat portion having a central aperture constructed and arranged to engage one of said contact points when both said guide and file are inserted between said points, and thereby retain said file blade in contact therewith.
- 45 8. A device of the character described, comprising a file having a blade and a stem said blade being wider than said stem, in combination with a guide having a sleeve slidably receiving said stem, said sleeve having one end slotted to receive said blade, and said guide having a portion opposite said blade and constructed and arranged to engage the element to be filed and thereby retain said file blade in contact therewith.
- 50 9. A device for filing contact points which are urged together, comprising in combination, an abrasive member comprising a stem and a file blade, and a guide comprising a sleeve slidably receiving said stem for rectilinear reciprocation therein and a substantially flat portion having an aperture no wider than said file blade constructed and arranged to engage one of said contact points when both said flat guide portion and said file blade are inserted between said points so as to cooperate with said sleeve to retain said file blade in engagement with the said contact.
- 55 10. A guide blade and an abrasive blade in parallel substantially contacting relation, said guide blade being provided with an aperture, and means confining the movement of said abrasive blade to a direction radial to said aperture, comprising a stem part of said abrasive blade passing through a retainer part of said guide.
- 60 11. A guide and a member slidably mounted thereon and having an abrasive surface means on said guide slidably retaining said member for rectilinear reciprocation therein, said guide having a substantially flat blade parallel to said surface and provided with an aperture adapted to engage and encircle the element to be abraded, said blade and abrasive surface being removable together from the element to be abraded.
- 65 12. A device for filing contact points which are urged together, comprising in combination, a guide and an element slidably mounted relative thereto, said guide comprising a single piece of sheet metal of a width less than half its length, said member having an abrasive surface, said guide having an aperture adapted to receive one of said contact points when both said guide and abrasive surface are inserted between said points, the guide having means confining said member to substantially rectilinear movement and stop means for the member cooperating with the guide for limiting the rectilinear movement of the member to prevent movement of said abrasive surface clear of said aperture.

HOWARD WILSON.
